BEAM

Geoffrey Benjamin Hern, Byecroft, Bircher, near
Leominster, England

Filed Dec. 1, 1964, Ser. No. 82,865

Claims priority, application Great Britain Oct. 2, 1964

Term of patent 14 years

(Cl. D13—1)

F/G. 1.

F/G. 2.

F/G. 3.

F/G. 4.

F/G. 5.

F/G. 6.

FIGURE 1 is an isometric view of a beam, showing my new design.

FIGURE 2 is a side elevational view of an end portion of said beam.

FIGURE 3 is an end view thereof.

FIGURE 4 is a section on line 4-4, FIGURE 1.

FIGURE 5 is a horizontal section on line 5-5, FIGURE 2.

FIGURE 6 is a plan of said beam.

The center of the beam is broken away to indicate an article of indefinite length, the design of the beam is repeated throughout as indicated.

I claim:

The ornamental design for a beam, as shown and described.
